UNITED STATES PATENT OFFICE.

GEORGE S. MOGYORÓS, OF DAYTON, OHIO.

ELEVATOR SAFETY DEVICE.

1,157,322.

Specification of Letters Patent. Patented Oct. 19, 1915.

Application filed March 19, 1915. Serial No. 15,456.

To all whom it may concern:

Be it known that I, GEORGE S. MOGYORÓS, a subject of the King of Hungary, residing at Dayton, in the county of Montgomery and State of Ohio, have invented certain new and useful Improvements in Elevator Safety Devices, of which the following is a specification.

This invention relates to certain new and useful improvements in elevator safety devices.

The primary object of this invention is to provide means carried by an elevator car automatically actuated upon a breaking of the hoisting cable for the purpose of lockingly engaging the sides of the elevator shaft for holding the car stationary and thereby preventing the car from falling to the bottom of the shaft and causing injury to the contents of the car.

A further object of the invention is the provision of oppositely slidable spring-pressed bolts carried by an elevator car and being retained retracted by means of engaging rods when the hoisting cable is supporting the car, the said rods being automatically released upon a severing of the cable, and whereby individual projecting means for the said bolts position the latter in locking engagement with the side beams of the shaft.

With these general objects in view and others that will appear as the nature of the invention is better understood, the same consists in the novel combination and arrangement of parts hereinafter more fully described, illustrated in the accompanying drawings, and pointed out in the appended claim.

In the drawings forming a part of this application and in which like-designating characters refer to corresponding parts throughout the several views:—Figure 1 is a front elevation of an elevator car provided with the present device and partially broken away, the same being positioned between the side beams of the shaft. Fig. 2 is a vertical transverse sectional view thereof. Fig. 3 is a view similar to Fig. 1, but with the elements in their locked position as assumed when the cable is broken. Fig. 4 is a detail transverse vertical sectional view through the upper portion of the car as normally positioned, and Fig. 5 is a perspective view of one of the locking bolts and its actuating lever detached.

Referring more in detail to the drawings, the side beams 10 are vertically positioned within the elevator shaft and are provided with inwardly positioned guide strips 11 having oppositely-positioned equally spaced notches 12 arranged therein. The elevator car 13 has a transversely position beam 14 at the top thereof, the opposite outer ends 15 of which are adapted for sliding upon the guide strips 11. The bottom 16 of the car is provided with a similar transversely positioned beam 17 upon the lower side thereof, and its opposite ends 18 are arranged to slidably-engage the strips 11 similar to the arrangement I described in connection with the upper beam 14.

The car bottom 16 is provided at opposite points with chambers 18, each of the same having a right-angular form of locking bolt 19 mounted therein, the engaging arm 20 of the said bolt being slidably positioned through a slot 21 opening at the adjacent outer edge of the car bottom and in alignment with the adjacent guide strip 11. A spindle 22 is provided upon the bolt 19 extending inwardly in alignment with the locking arm 20 thereof and is slidably journaled in a perforated bracket 23 within the chamber, while an expansion spring 24 encircles the said spindle and bears between the locking bolt and the bracket 23.

A vertical slidable rod 25 is slidably mounted at each side of the car through vertical alining perforations 26 and 27 in the upper and lower beams 14 and 16 respectively, one of the rods 25 being thus provided for each of the locking bolts 19 and being in alignment with a perforation 28 of such bolt, when the bolt is retracted. A resetting lever 29 is provided for each of the bolts 19, the said levers being pivoted as at 30 to the adjacent portion of the car and having a pivotal link connector 31 between the lower end of the lever and the projecting arm 32 of the locking bolt. By this construction, it will be seen that when the rod 25 is engaged within the perforation 28 of its respective locking bolt, the said bolt will be retained retracted and at which time its spring 24 will be compressed, while an upward movement of the rod 25 will release the locking bolt, thus allowing its spring 24 to automatically project the bolt, and whereby the same will engage the adjacent one of the said guide strip notches 12. By outwardly moving the lever 29, the spring will

be again compressed and the perforation 28 of the bolt brought into alinement with the adjacent rod 25 which may be positioned therethrough by the means hereinafter set forth.

The upper beam 24 of the car is provided with upright brackets 33 in the bifurcated tops 34 on which oppositely projecting levers 35 are freely pivoted, while the opposite outer ends of the levers 35 are provided with longitudinal slots 36 having transverse bolts 37 mounted therein which are secured to the upper free ends of the rods 25. The inner ends of the levers 35 are pivoted 10 to an upright post 38 slidable through the top of an arch-shaped bracket 39 carried by the top beam 14 of the car, the hoisting cable 40 being secured within a top ring 41 of the said post. The post is also provided 15 with a lower ring 42 having a normally closely coiled retractile spring 43 having one of its ends secured therein and its other end secured to a staple 44 centrally arranged upon the said beam 14.

Opposite lugs 45 are arranged upon the bracket 39 and oppositely arranged chains 46 are connected between the said lugs and staples 47 which are positioned upon opposite sides of the post adjacent the ring 41 thereof.

From this detailed description of the device, the complete operation of the same will be at once apparent in that a disengagement of the side rod 25 from the locking bolts automatically allows a projecting of the bolts into locking engagement with the notches 12, it being understood that the said rods 25 are retained in their lower locking positions by means of the levers 35, when the inner ends thereof are in their upper positions being held by the cable 40, as best illustrated in Fig. 1. In the event that the cable becomes broken as illustrated in Fig. 3, the spring 43 contracts and draws downwardly the inner ends of the levers 35 thus moving upwardly the rods 25 and releasing the same from the locking bolts and whereupon the projection springs 24 force the bolts outwardly and the engagement thereof

with the notches 12 retains the car stationary within the shaft.

A hand lever 48 is pivoted as at 49 adjacent each of the rods 25 and has a sliding pivotal connection 50 therewith for the purpose of vertically moving the rod when desired by the operator of the car.

While the form of the invention herein shown and described is what is believed to be the preferred embodiment thereof, it is nevertheless to be understood that minor changes may be made without departing from the spirit and scope of the invention as set forth in the claim.

What I claim as new is:

A device of the class described comprising in combination with oppositely-arranged guide strips having oppositely positioned notches therein, an elevator car vertically movable between the said strips, and having chambers in the bottom of said car, right-angled locking bolts slidably mounted within the said sockets and adapted for projecting outwardly in the plane of said notches, projection springs for the said bolts, bolt retaining rods vertically journaled at opposite points in the top and bottom of the said car, an arch bracket carried by the car top, an upright post slidably arranged in the said bracket, a hoisting cable for the car secured to the upper end of the said post, opposite limiting chains connecting the opposite points upon the said arch bracket, and the upper portion of the said post, oppositely arranged levers pivotally mounted intermediate their ends and having their outer ends shiftably pivoted to the upper ends of said rods and their inner ends pivoted to the lower end of the said post, and a coil spring attached between the lower end of the said post and a substantially central point upon the top of the car.

In testimony whereof I affix my signature in presence of two witnesses.

GEORGE S. MOGYORÓS.
